(57) **CLAIM**

The ornamental design for a surveillance camera housing, as shown and described.

DESCRIPTION

FIG. 1 is a top, front and left side perspective view of a surveillance camera housing showing my new design;

FIG. 2 is a front elevational view thereof;

FIG. 3 is a left side elevational view thereof, the undisclosed right side elevational view being a mirror image of that shown in FIG. 2; and,

FIG. 4 is top plan view thereof, the undisclosed bottom plan view being a mirror image of that shown in FIG. 3.
